DESIGN FOR A WEIGHING SCALE

Henry Dreyfuss, New York, N. Y., assignor to
Fairbanks, Morse & Co., Chicago, Ill., a corpora-
tion of Illinois

Application June 22, 1944, Serial No. 114,143

Term of patent 14 years

(Cl. D52—10)

To all whom it may concern:

Be it known that I, Henry Dreyfuss, a citizen
of the United States, residing at New York city,
in the county of New York and State of New
York, have invented a new, original, and orna-
mental Design for a Weighing Scale, of which
the following is a specification, reference being
had to the accompanying drawing, forming part
thereof.

In the drawing

Fig. 1 is a top plan view of a weighing scale,
showing my new design;

Fig. 2 is a side elevational view thereof;
Fig. 3 is an elevational view of one end there-
of, and

Fig. 4 is an elevational view of the opposite end
thereof.

I claim:

The ornamental design for a weighing scale,
as shown.

HENRY DREYFUSS.
